UNITED STATES PATENT OFFICE.

ZEPHANIAH E. WILLIAMSON, OF SHEFFIELD, ILLINOIS.

RAILWAY-SIGNAL.

No. 895,061.

Specification of Letters Patent.

Patented Aug. 4, 1908.

Application filed November 30, 1907. Serial No. 404,491.

To all whom it may concern:

Be it known that I, ZEPHANIAH E. WILLIAMSON, a citizen of the United States, residing at Sheffield, in the county of Bureau 5 and State of Illinois, have invented a new and useful Improvement in Railway-Signals, of which the following is a specification.

This invention relates to improvements in means for announcing the approach of trains 10 or single cars on a railroad track, at crossings, stations or other points desirable and particularly to that class in which audible signals are given by a gong or bell, and the objects are: to provide mechanical means 15 that will cause a bell to ring repeatedly as each wheel passes a point, or points, in its approach to the bell location, and also, to provide such means in forms not easily disarranged, which are not subject to climatic 20 or storm conditions, or affected by frost or rust and which are simple in arrangement and inexpensive in application. These objects are attained by the novel combination and arrangement of parts hereinafter fully 25 described and shown in the accompanying drawings, forming part of these specifications, and in which:

Figure 1, is a side elevation of a railroad track having the invention applied. Fig. 2, 30 is a plan view of the same. Fig. 3, is an enlarged side elevation of the operative mechanism and, Fig. 4, is an end view of the same shown in position.

The invention consists of an elliptical 35 spring comprised of two independent leaves 1 and 2, hinged together at their ends 3, in such manner that when the leaves are forced towards each other, as by pressure applied to the upper leaf, the ends may move freely outward, but return to the normal position when the pressure is removed. The lower leaf 2, is firmly secured at the middle of its length and lowest point by a clamp 4, or equivalent means bolted to a cross tie or sleeper used in 45 supporting the rails and close to the inner side of the outer rail on which the cars may approach. The upper leaf 1, is provided at its center and highest point, which is arranged approximately level with the head of 50 the rail, with a depending lug or projection 5, to which is attached the end of a flexible connection, as a chain 6, the same running over a pulley 7, pivotally secured on a bracket 8, which may be part of the clamp 4, or separate 55 from it as is preferred. The chain continues under a similar pulley 9, on the

bracket 10, and passes over a series of guide pulleys 11, around the pulley 12, under and beyond the track-rail to the pulley 13, at the foot of the post 14; here it may enter, if the post be hollow, or follow up the side, if the post be solid, connect with the spirally wound spring 15, attached to the post and carrying the bell 16, in such manner that the bell is caused to ring whenever the chain or other connecting means be pulled. This is accomplished each time the spring leaf 1, is depressed, which is done by the pressure of car-wheel flanges contacting with the leaf in its passage over it. A suitable covering may 70 be provided to guard and protect the connections, the same being disposed on or beside the track, to prevent possible injury thereto.

Obviously the arrangement of the bell support is such that the bell will ring several 75 times when the spring support is put in motion and that such motion will be transmitted to it by the contact of every wheel passing over the elliptical spring at the side of the rail; a car approaching either head on 80 or backing will produce the same results.

The simplicity of the device will be apparent as well as the entire absence of any minor springs or parts liable to rust and hence fail to operate at possible critical moments.

No changes are made in the application of 85 the device to the rails or road-bed and no disfigurement to the road-way is caused thereby.

As many of the elliptical springs may be used as desired, preferably at distances of 90 five, three and two hundred feet from the signal post and all connected to the same bell, which is located usually at crossings where watchmen are not regularly stationed, or the same may be used in connection with 95 watchmen as cautionary signals.

Such modifications may be made as in the use of a combination of chains and rods in the connections and also in the location of the same, whether upon the ties direct or 100 upon posts beside the track, without departing from the scope of the claim.

Having thus described my invention, what I claim as new and desire to secure by Letters Patent of the United States, is

In a railway signal, the combination of a rail, a tie supporting the same, a rail clamp securing the rail to the tie, an elliptical spring mounted on said clamp, said spring comprising upper and lower leaves pivotally connected at the adjacent opposite ends thereof, the upper leaf having a central depending 110

lug on its under side, brackets mounted on the rail clamp, pulleys on said brackets and arranged at a right angle to each other, a flexible connection passing under one pulley 5 and over the other to the lug of the upper spring leaf, a fastening securing said connection to the lug, an alarm, and means securing the flexible connection to the alarm.

In testimony whereof I have hereunto signed my name to this specification in the 10 presence of two subscribing witnesses.

ZEPHANIAH E. WILLIAMSON.
